(74) Attorney, Agent, or Firm — Randy K. Chang

(57) **CLAIM**

The ornamental design for golf club head, as shown and described.

DESCRIPTION

FIG. 1 is a perspective sole view of a golf club head showing our design;

FIG. 2 is a bottom plan view thereof;

FIG. 3 is a rear elevation view thereof;

FIG. 4 is a toe end view thereof;

FIG. 5 is a heel end view thereof;

FIG. 6 is a top plan view thereof; and,

FIG. 7 is a front elevation view thereof.

The broken lines showing on the top of the hosel, the bottom surface of the golf club head and the engagement mechanism of the screw head forms no part of the claimed design.

1 Claim, 3 Drawing Sheets(56)
